UNITED STATES PATENT OFFICE

WILLIAM H. KLAUER, OF DUBUQUE, IOWA

METHOD OF MAKING PIPE HANGERS

Application filed July 18, 1927. Serial No. 206,709.

This invention relates to the manufacture of hangers such as are used to fasten rain spouts or conductor pipes to walls; and the invention has for an object to provide a simple and rapid method for producing such hangers.

Heretofore, it has been found difficult to produce hangers of this kind by stamping, since the blanks from which the hangers are formed terminate in narrow shanks, so that any inaccuracy in stamping will cause the metal thereof to flow and thereby spoil the blank. This difficulty has, in the past, been avoided to some extent by arbitrarily making the blanks wider, which is, of course, wasteful of metal, or by using other methods of manufacture, which are usually more costly than stamping. The present invention aims to remedy these objections while producing, by stamping, an improved product. This is accomplished by stamping double blanks and subsequently splitting the double blanks to form single blanks, and by other novel features, as will hereinafter be disclosed.

Further objects of the invention will appear from the description, taken in connection with the accompanying drawings, in which,

Fig. 1 illustrates the manner of cutting double blanks from the sheet metal;

Fig. 2 shows one of the double blanks split along its longitudinal axis;

Fig. 3 shows one of the blanks having its end flattened;

Fig. 4 shows the blank after the pointing operation;

Fig. 5 shows the completed hanger;

Fig. 6 is a sectional view of a special die used to bend the hangers; and

Fig. 7 is a sectional view taken on the line 7-7 of Fig. 6.

As the first step in the method, a strip of sheet metal 9 is provided, of a width equal to the length of the hangers to be made therefrom. From this strip are stamped a plurality of double blanks 10, each of the blanks having a shank 11 and an enlarged portion 12, the enlarged portion of each double blank being cut from the metal between the shanks

of the two adjacent blanks, so that adjacent blanks are in reversed position, as indicated in Fig. 1.

Cutting the blanks in this manner leaves slugs 14 of regular shape which may, without machining, be used as elements in making pipe clamps or other manufactured articles. It will be noted that a minimum of waste is produced by this method and that each of the shanks is of sufficient width that it may be stamped without danger of causing any objectionable flow of metal.

The next step in the method is to split the double blank along its central axis to form two single blanks 13, as shown in Fig. 2. Each of the single blanks is of a size to form a convenient hanger, and has a head 16, and a narrow tapered shank 17. A shoulder 18 is provided at the junction of the head and shank, and form a driving head adapted to receive the hammer blows when the hanger is driven into place. The process for each blank and the form of the blanks being exactly alike, the process as applied to but one of the blanks will now be described.

As the next step in the process, the blank is then swaged or flattened at its end 15 by a stamping operation which causes the metal to flow to each side of the normal edge line of the blank, so as to form the end into an approximate wedge shape, as shown in Fig. 3.

As the next step, the end 15 is trimmed by shearing off the excess metal flowed beyond the normal edge lines of the blank to bring the end 15 approximately to a point, which is adapted to be driven into a wooden or masonry wall.

The final step is bending the shank 17 to the shape shown in Fig. 5, whereby the shank 17 is adapted to partially encircle the pipe or other object to be secured by the hanger.

This bending operation is performed by the apparatus shown in Figs. 6 and 7, which comprises a female member 20 having two shoulders 21 and 22 and a channel 19 therebetween. Vertical supporting flanges 23 are secured to shoulder 21 and to the surface of the channel 19, and are spaced from each other a distance equal to the thickness of one of the blanks 13, so that a groove is formed between

each two adjacent flanges 23 for the purpose of holding the blanks against overturning during the bending operation. The flanges 23 are preferably seated in recesses 5 in the member 20, but may be secured thereto by any other suitable means, or may be formed integral with the member 20. The other shoulder 22 is likewise provided with vertical supporting flanges 25 in alinement 10 with flanges 23 and spaced from each other to form grooves adapted to receive the shanks of the blanks to be bent.

A longitudinal recess 26 is formed along the inner edge of the shoulder 21, and a holding and pivoting block 27 is seated in said recess. Block 27 is so shaped that two of its longitudinal faces meet in an acute angle to form an edge 28, which is of such sharpness and hardness as to bite or cut into the 20 blanks sufficiently to prevent slipping or displacement thereof during the bending operation. The blanks pivot about this hardened edge 28, so that a more exact conformation to the form of the die is produced.

25 The male member 30 of the die is provided with a removable head 29 having vertical supporting flanges 31 spaced from each other in a manner similar to the flanges 25 and in alinement therewith.

30 The operation of the device will be evident from the preceding description, but for convenience, the cycle of operations may be briefly outlined as follows:

35 The double blanks are first stamped from a strip of sheet metal, and each blank is then split to form two single blanks. Each single blank then has its end 15 flattened, and the excess metal is then sheared off to leave a point. A plurality of these blanks are then placed 40 upon the female die member in an edgewise position with the driving head shoulders 18 downward and in such position as to be engaged by the block 27. As the male member comes into contact with the blanks, the blanks 45 enter the grooves formed thereon and the blanks are bent to shape without the possibility of overturning. As the blanks bend, each one is caught upon the edge of the block 27 and held against lengthwise movement 50 until the male member is released.

Having described my invention, what I claim as new and desire to secure by Letters Patent of the United States is:

1. A method of making pipe hangers, comprising stamping from sheet metal a double blank having a head portion and a shank portion and driving head shoulders on the edges of the blank separating said head and shank portions, said shoulders being located 55 at a distance from the transverse axis of the blank, said blank being symmetrical about its longitudinal axis, splitting said blank along its longitudinal axis to form two single blanks having head and shank portions, and bending the shank portions of the blanks in 60

the planes of the sheet metal and away from said shoulders to pipe engaging form.

2. A method of making pipe hangers, comprising stamping from sheet metal a double blank symmetrical about its longitudinal axis 70 having a head portion and a shank portion and driving head shoulders on the edges of the blank separating said head and shank portions, the transverse axis of the blank passing through the shank portion, said shoulders being located at a distance from 75 said transverse axis and on the same side thereof as said head portion, the head portion being wider at said shoulders than the shank portion, the edges of the head portion sloping inwardly from the shoulders to the end of the blank, whereby when the blank is split along its longitudinal axis said head portion will be divided into two spike portions, splitting said blank along its longitudinal axis to form two single blanks of the 80 same shape but oppositely disposed, said single blanks each comprising a shank portion and a spike portion, the shank portion being 85 longer than the spike portion, one edge of the blank being straight, the other edge having a driving head shoulder separating the shank and spike portions, the spike portion at said shoulder being wider than the shank portion, the other edge of the spike portion sloping inwardly from the shoulder to the 90 end of the blank, then bending the shank portions in the plane of the sheet metal in the direction of the longitudinal axis of the double blank and away from the shoulders into 95 pipe engaging form.

3. A method of making pipe hangers, comprising stamping from sheet metal a double blank having a head portion and a shank portion and driving head shoulders on the edges of the blank separating said head and shank portions, said blank being symmetrical about its longitudinal axis, splitting said blank along its longitudinal axis to form 100 two single blanks having head and shank portions, and bending the shank portions of the blanks in the planes of the sheet metal and away from said shoulders to pipe engaging form.
